CLAIM

We claim the ornamental design for label with pad of labels, as shown and described.

DESCRIPTION

FIG. 1 is a top perspective view of a label embodying our new design.
 FIG. 2 is a top plan view of the label of FIG. 1.
 FIG. 3 is a bottom plan view of the label of FIG. 1, the bottom surface of the label having a region of adhesive.
 FIG. 4 is a front-edge elevational view of the label of FIG. 1.

FIG. 5 is a back-edge elevational view of the label of FIG. 1.
 FIG. 6 is a left-side elevational view of the label of FIG. 1.
 FIG. 7 is a right-side elevational view of the label of FIG. 1.
 FIG. 8 is a top perspective view of an alternative embodiment showing a pad of labels that includes the label of FIG. 1 with a bottom carrier sheet.
 FIG. 9 is a top plan view of the pad of labels of FIG. 8.
 FIG. 10 is a bottom plan view of the pad of labels of FIG. 8.
 FIG. 11 is a front-edge elevational view of the pad of labels of FIG. 8.
 FIG. 12 is a back-edge elevational view of the pad of labels of FIG. 8.
 FIG. 13 is a left-side elevational view of the pad of labels of FIG. 8.
 FIG. 14 is a right-side elevational view of the pad of labels of FIG. 8.
 FIG. 15 is a top perspective view of an alternative embodiment showing two pads of labels that include the label of FIG. 1 with a shared bottom backing card.
 FIG. 16 is a top plan view of the two pads of labels of FIG. 15.
 FIG. 17 is a bottom plan view of the two pads of labels of FIG. 15.
 FIG. 18 is a front-edge elevational view of the two pads of labels of FIG. 15.
 FIG. 19 is a back-edge elevational view of the two pads of labels of FIG. 15.
 FIG. 20 is a left-side elevational view of the two pads of labels of FIG. 15.
 FIG. 21 is a right-side elevational view of the two pads of labels of FIG. 15.
 FIG. 22 is a top perspective view of an alternative embodiment showing three pads of labels that include the label of FIG. 1 with a shared bottom backing card.
 FIG. 23 is a top plan view of the three pads of labels of FIG. 22.
 FIG. 24 is a bottom plan view of the three pads of labels of FIG. 22.
 FIG. 25 is a front-edge elevational view of the three pads of labels of FIG. 22.
 FIG. 26 is a back-edge elevational view of the three pads of labels of FIG. 22.
 FIG. 27 is a left-side elevational view of the three pads of labels of FIG. 22.
 FIG. 28 is a right-side elevational view of the three pads of labels of FIG. 22.
 FIG. 29 is a top perspective view of another label embodying our new design.
 FIG. 30 is a top plan view of the label of FIG. 29.
 FIG. 31 is a bottom plan view of the label of FIG. 29, the bottom surface of the label having a region of adhesive.
